INVENTOR.

UNITED STATES PATENT OFFICE.

JOHN DAVID YEAGER, OF PHILADELPHIA, PENNSYLVANIA.

SHOE.

Application filed November 19, 1921. Serial No. 516,447.

To all whom it may concern:

Be it known that I, JOHN DAVID YEAGER, a citizen of the United States, residing at 103 So. 63rd St., Philadelphia, in the county 5 of Philadelphia and State of Pennsylvania, have invented a new and useful Improvement in Shoes, of which the following is a specification.

My improvement in shoes relates to wrinkles that occur in the leather vamps of shoes that rub or bite down on the large toes in 10 back of the tips. These wrinkles are caused by the plumpness of the leather contracting a sharp firm wrinkle, due to the rough side 15 of the vamp leather clinging to the roughness of the fabric linings and bearing down on the large toes at every step, which rubs a blister and tortures the wearer to unlimited agonies.

20 My improvement consists of a piece of fabric with glazed sides, one half inch wide and in lengths varying to conform with the various sizes of shoes, extending from the vamp seams, where it is stitched to vamp, across 25 the vamp to the toe boxes, between the vamp leather and the fabric linings; and left loose (not stitched fast), so as to have free action in every step taken by the foot.

This fabric being inserted at this location 30 on each shoe (over the line of the large toes) prevents the rough sides of the vamp leather from clinging to the rough sides of the fabric linings, and acts as a slide for the vamp leather, preventing the friction of the vamp 35 leather wrinkles, thus allowing the fabric linings to be free of the vamp leather and follow the bend of the toe joints, without the sharp pressure of the vamp leather wrinkles bearing down on the large toes.

40 This fabric is inexpensive, fine and thin and resists perspiration, also undetectable after insertion in the shoes, being thin, though tough and durable and cannot be felt by the wearer and still stand wear for this purpose.

45 Figure 1 is a top view of the vamp and toe of a shoe partly broken away, Figure 2 is a sectional side view of the inside of a shoe in normal position. Figure 3 is a sectional side view of the inside of a shoe in a 50 stepping position or walking position.

Similar letters refer to similar parts throughout the three views.

Figure 1 shows the location of the improvement (E) which is on the inner sides of the vamp (D) one quarter inch from the 55 centre line of the vamp and stitched to the vamp seam (F), extending across the vamp (D) to a point beyond the end of tip (B) which end is not stitched (G), between the vamp leather (D) and the fabric linings 60 (C).

Figure 2 shows the location of the improvement (E) in a normal position, extending from the vamp seam (F) where it is stitched, to the point beyond the end of 65 the tip (B) where it is not stitched (G) between the vamp leather (D) and the fabric linings (C).

Figure 3 shows the location of the improvement (E) which is stitched fast at 70 vamp seams (F) and extending across vamp to a point beyond the end of tip (B) where it is left loose (G) (not stitched) which separates vamp leather (D) from the 75 fabric linings (C) and the wrinkle in the vamp leather (D) in back of the tip (B) which rubs down on the toes, and the fabric linings (C) which are separated from the vamp leather (D) by the improvement (E) which minimizes the friction of the 80 vamp leather wrinkles (D).

I am aware that prior to my invention, fabric with glazed sides has been used for other purposes, but I am not aware that fabric with glazed sides has been used for the 85 purpose of my invention, substantially as described and substantially as shown.

I claim:

A shoe comprising a vamp, a vamp lining and a strip of fabric, glazed on both sides, 90 extending over the top of the foot between the vamp and lining and between the vamp throat seam and the tip seam, secured at the former and free at the latter.

JOHN DAVID YEAGER.

Witnesses:

WILLIAM YEAGER,
LILLIAN B. YEAGER.
